OPEN ELECTRIC ARC LAMP AND UNIT OF
ELECTRODES THEREFOR

Adolf Bayerl, Bilthoven, Netherlands

Application June 29, 1950, Serial No. 170,987
In the Netherlands July 6, 1949

6 Claims. (Cl. 313—331)

1

This invention relates to a set of electrodes for single use in an open arc lamp, especially for irradiating purposes in therapeutics, in which the electrodes have their rear ends equipped with contacting members and their fore ends rigidly spaced apart a predetermined distance, said electrodes and said contacting members forming an integral unit of substantially the same size as the set of electrodes.

The manipulation of electrode units of the standard kind is rather difficult, especially when the electrodes consist of nonoxidizable substances and are, therefore, very small in size. Before each use of the arc lamp the contacting members have to be rigidly secured to the junction terminals of the lamp and, after cessation of the irradiating operation, the electrodes have to be loosened from the said junction terminals and thereupon removed one by one from the lamp, since the customary conducting bridge interposed between the fore ends of the electrodes for initiating the ignition of the electric arc is evaporated or burnt off during the operation of the lamp, so that the initial electrode unit is divided into two separate parts. When the lamp is still very hot, the replacement of the electrode unit by a new one requires much time and trouble.

An object of the invention is to overcome these drawbacks and to facilitate the insertion as well as the removal of the set of electrodes in an open arc lamp. A further object is to provide an arrangement by which the electrodes can be handled as an integral unit during as well as after their use in the arc lamp.

A still further object of this invention is to provide units of this kind with more than one pair of electrodes, in order to form a plurality of electric arcs, simultaneously or consecutively.

Another object of the invention is to provide an open electric arc lamp of special construction in which the above mentioned units of electrodes can be applied with advantage.

With these and other objects in view the invention will now be more fully described with reference to the accompanying drawings in which a practical embodiment of an open arc lamp and electrode units used in combination therewith in accordance with the invention are illustrated by way of example. In the drawings:

Fig. 1 is a sectional view of an open arc lamp comprising an electrode unit in accordance with the invention.

Fig. 2 shows, on a larger scale, part of a section taken on the line II—II in Fig. 1.

Fig. 3 is a side view of a unit, according to the invention, comprising two pairs of electrodes.

The open arc lamp shown in Fig. 1 comprises a casing 1 surrounding the reflector 2 and the guides 3a and 3b for reception of an electrode unit used in combination with this lamp in accordance

2

with the invention. The guides comprise two parallel channel-shaped conductive rails 3a and 3b which are closed at their lower ends and arranged with their open channelled sides in face-to-face relationship. The conductive rails 3a, 3b are secured to an insulated body 4 on which is mounted a funnel-shaped inlet member 5. Junction terminals 6 and 7 electrically connect said rails 3a and 3b, through suitable wires, to a source of current (not shown).

In the conducting guides 3a, 3b a unit 8 is arranged comprising two electrodes 9 and 10 clamped in holders 11 and 12, respectively, said holders being preferably made of copper. Each of these holders or contacting members consists of a strip which is turned up at its lower end so as to embrace the electrode (see Fig. 2), while a part of its upper end is doubled back upon itself to form a clamp 13 for a sheet 14 of mica serving as a lateral connecting member between the electrodes 9 and 10. Between the front ends of the electrodes 9 and 10 a conductive bridging member 15 of graphite is provided. A rigid metal wire 17 passes at 16 through the insulating connecting sheet 14 and is bent in the shape of a hook at its lower extremity to support said connecting sheet 14. The upper extremity of the wire 17 is bent to form a handle 18.

In assembling the electrode unit of this invention, the unit comprising the electrodes 9 and 10 is carried by the handle 18 and introduced into the lamp through the inlet member 5 and along guides 3a, 3b, this can be done without danger, even if current is on, because the handle 18 is insulated through connecting member 14. The unit is lowered until it abuts against the end walls 19 and 20 of the guide channels 3a and 3b. If the current is on the lamp will immediately ignite, and the bridge 15 will gradually disappear. Similarly the electrode unit can be withdrawn from the lamp by means of the wire 17, also without danger, and with the current on, whereupon the irradiating operation will cease. The removed unit of electrodes may be discarded and immediately replaced by a new one.

In some instances it may be advantageous to make use of units comprising more than one pair of electrodes, in order to obtain a plurality of electric arcs. The pairs of electrodes may be arranged in parallel or in series. A unit of this kind comprising two pairs of electrodes is shown in Fig. 3. This unit consists of two outer holders 11 and 12 for the electrodes 9 and 10 and an intermediate holder 21 for an electrode 22, whereby two electric arcs are formed, viz. between the electrode 9 and the left extremity of the intermediate electrode 22 and between the electrode 10 and the right extremity of the electrode 22, respectively. The holders 11, 21 and 12 are attached to the lateral connecting member 14 by

means of rivets 23. In this embodiment the bridging members 15 are applied on the lower sides of the electrodes between the conductive holders 11, 21 and 12.

It will be evident that the various pairs of electrodes in a single unit may be arranged also in such a manner that the electric arcs are formed consecutively instead of simultaneously. Instead by means of the bridging members 15 attached to the electrodes or to the holders thereof, the ignition of the arc may be effected by separate conducting pieces which are temporarily brought into contact with the electrodes bodies.

What I claim is:

1. In an electrode unit for arc lamps comprising spaced electrodes, the provision of insulated handling means permanently bridging said electrodes.

2. In an electrode unit for arc lamps comprising spaced pairs of electrodes, the provision of insulated handling means permanently bridging said pairs of electrodes.

3. In an electrode unit for arc lamps comprising spaced electrodes, the provision of an insulated bridge permanently connecting said electrodes and handling means connected to said bridge.

25

4. In an electrode assembly for arc lamps comprising spaced electrodes, the provision of a bridge permanently connecting said electrodes, means for insulating said bridge and means associated with said bridge for insertion and removal of said electrode assembly from an arc lamp.

5. An open arc lamp comprising in combination, a lamp casing, an inlet in said casing, spaced electrically conductive retaining means within 10 said casing in alignment with and insulated from said inlet, means for connecting said retaining means with a source of power, and an integral electrode unit for location in said retaining means comprising spaced electrodes, an insulating bridge permanently connecting said electrodes and a projecting handle secured to said bridge and extending outwardly through said inlet.

6. An open air lamp as claimed in claim 5, wherein said retaining means comprises a pair 20 of parallel channelled guide members and seats in said members for reception of the mutually remote ends of said electrodes.
